UNITED STATES PATENT OFFICE.

JOSEPH FRANKLIN TWIST, OF SAN FRANCISCO, CALIFORNIA.

APPARATUS FOR MAKING SEAMLESS TOOTH-CROWNS.

SPECIFICATION forming part of Letters Patent No. 660,319, dated October 23, 1900.

Application filed January 9, 1900. Serial No. 877. (No model.)

To all whom it may concern:

Be it known that I, JOSEPH FRANKLIN TWIST, a citizen of the United States, residing in the city and county of San Francisco, State of California, have invented an Improvement in Apparatus for Making Seamless Tooth-Crowns; and I hereby declare the following to be a full, clear, and exact description of the same.

My invention relates to an apparatus for the manufacture of seamless tooth-crowns.

It consists in a mechanism for forming the crowns and a means for fitting and adapting them to the position in which they are to be used.

It also comprises details of construction, which will be more fully explained by reference to the accompanying drawings, in which—

Figure 1 is a vertical section of a base, die, and guide with a punch. Fig. 2 is a horizontal section of adjustable guide through x , Fig. 3. Fig. 3 is a vertical sectional view of the same, partially in elevation. Fig. 4 is half of flask with moldine and castor pattern. Fig. 5 shows the other half of flask empty. Fig. 6 shows half of metal cast with pattern embedded. Fig. 7 is a vertical section of final former.

In the formation of what are known as "seamless tooth-crowns" it is first necessary to make the crown from a disk of gold. This is generally effected by forcing the disk through successive holes in a die-plate, by which the rim or flange is gradually turned up around the central portion until the proper size has been produced. The first part of my invention relates to an improved mechanism for performing this work at a minimum of labor and expense.

As shown in Fig. 1, the base A has a central hole countersunk to receive the die 2, which is fitted therein. This die has a hole made through it, the upper edge being beveled so as to prevent its breaking or tearing the metal of the disk which is to be forced through the die. These dies fit loosely into the central socket, and any number of them may be fitted to the same socket, the interior of each being successively smaller than the preceding one, so that by continuously forcing the disk and the crown which is being formed

from it through these decreasing dies the sides will be turned up and the diameter of the whole crown decreased until it reaches the desired size. In order to effect this, it is necessary to have punches 3, which fit each of the various dies 2 used. These punches are formed upon the lower end of a shank 4, which shank is always maintained of a certain diameter in all the punches.

55 60 65 70 75 80 85 90 95 100
5 is a guide through which the shank 4 is slidable, this guide being of sufficient diameter to receive and direct 4 when the punch 3 is forced down through the die 2. The guide 5 has at the bottom a circular rim or flange which fits into a correspondingly-shaped depression in the top of the stand or support A. This maintains the guide central and with its own axis in line with the axes of the various dies which are used during the operation. With this construction, it is only necessary to reduce the lower portion 3 of each punch to correspond with the die with which it is to be used, while the upper portion 4 remains of the same size in all of the punches, so that they all fit the single guide 5. In order to still further reduce the expense of the punches, each punch may be made of a single bar or rod having the same diameter throughout its length. In this case the guide consists of the outer cylinder 5 fitting the stand A, as before described, and having the central opening coincident with that of the dies 2. Within this outer cylinder are the radially-disposed vertical wings 6, movable in slots in the body of the casing, and these wings are normally retracted in the slots by a spring or springs 7. The upper and lower ends of the casing 5 are closed by caps having the eccentric or cam-shaped shallow grooves or channels 8 made in them, into which the upper and lower ends of the wings 6 extend, as shown in sectional view, Fig. 3. The slotted central body in which the wings are carried is turnable within the outer casing 5 by means of a projecting pin 9, which extends outwardly through a groove or slot 10, made circumferentially through the side of the outer casing 5. When by means of this pin the inner body and the wings are turned within the outer casing, the upper and lower ends of the wings in contact with the cam-

shaped grooves 8 will be either advanced or retracted in unison as they are turned in one direction or the other.

A scale may be marked along the slot 10 with figures indicating the size of punch that is to be used when the device has been turned to any particular figure. Thus when turned so that the wings are retracted to their fullest extent the largest-sized punch may be used, 10 and the disk which is to be formed into a tooth-crown being laid upon the die 2 the punch is pressed or driven down upon it, and it will be forced through the die and a peripheral flange turned up. A die of the 15 next smaller size being then placed in position, the corresponding punch is selected, and by turning the wings to the next figure they will be moved toward each other, thus forming a guide which will receive the next 20 smaller-sized punch, and the operation is thus repeated until the crown is of the proper diameter. By the use of this device the cost of punches is materially reduced, since they need be only simple straight rods and 25 the guide-wings can be adjusted to suit any size which is to be driven through.

The die, which is formed to correspond with the tooth, is made by taking a flask formed in two sections 11 and 12, with tongues 30 and grooves which cause them to register properly when placed together, and pressing a yielding material called "moldine" into the chamber formed in one of the halves. A previously-prepared plaster-of-paris cast 13, having 35 the exact form desired, is then pressed into this material until one-half of it is embedded. The two parts are then put together and the half which has not been filled with the molding material is filled with a suitable 40 fusible metal which flows around the half of the cast which has not been embedded in the moldine. When this is sufficiently cool, the flask is separated and the moldine is removed from the half which it occupied, thus leaving 45 the other half of the cast projecting from the metal with which one side has been filled. Soapstone or any suitable material being spread over the surfaces to prevent undue adherence, the flask is then put together and 50 fusible metal poured into the half previously occupied by the moldine, thus entirely surrounding the cast and forming a two-part matrix 14 when the cast has been removed. This is done by separating the parts of the 55 mold and the two metal sections 14, which have been cast within it, and this leaves a matrix, which is afterward filled up with fusible metal, precaution being taken to prevent its adherence to the matrix, and this 60 being completed is then ready for the application and fitting of a tooth-crown. A suitably sized and shaped crown being selected, it is placed over the end of the metallic die 15 which has been formed, and the latter is 65 then replaced into the metal matrix 14, and the parts again fitted together. The outside of the matrix 14 thus formed is made slightly

tapering by the shape of the hollow mold in which the two parts have been cast, and it is then inserted into a sleeve 16, having a correspondingly-shaped conical interior to receive it. The outside of the part 16 is screw-threaded, and a cap 17, having corresponding screw-threads and handles 18, by which it is turnable, is fitted to turn upon the part 70 16. Before applying this, however, a concave-faced pressure-block 19 is fitted into the interior of the cap 17, and this block has a pin 20, which projects up through a corresponding central hole in the top of the cap 80 17. The concaved face rests upon the outer end of the metallic die 15 previously described, and when the screw-cap 17 is turned down the part 19, pressing upon the projecting end of the metallic die 15, forces it downward, so as to 85 exactly shape the top of the tooth-crown to fit the end of the matrix. At the same time by reason of the conical shape of the interior of the part 16 the forcing of the two-part mold or matrix 14 into this cone will compress it transversely, and the crown will thus be perfectly shaped and fitted to the die. The latter is 90 afterward removed by fusing it, and the crown is left in perfect shape and adapted to the position where it is to be applied. 95

Having thus described my invention, what I claim as new, and desire to secure by Letters Patent, is—

1. In an apparatus for forming seamless tooth-crowns, a device for primarily shaping the crowns consisting of a series of dies, and a supporting-stand, a guide fitting said stand concentrically with the dies and punches, each punch conforming in diameter to a corresponding die, and all the punches slideable 100 through said guide and adapted to shape the crown by passing through the die upon which the crown has been laid, and means by which the guide is adjustable to punches of different 105 diameters. 110

2. A device for forming seamless tooth-crowns consisting of a die-supporting stand, a series of dies, punches movable through the dies, a guide of variable diameter supported upon the stand concentric with the dies and 115 means adapted to fit said guide to any size of punch. 120

3. In a device for forming seamless tooth-crowns, a die-supporting stand, a series of dies, punches corresponding in diameter with the dies, a variable guide fitting the stand concentrically with the dies, consisting of radially-slidable guide-wings between which the punch is movable and means for varying the distances of said wings from the center. 125

4. A device for forming seamless tooth-crowns consisting of a die-supporting stand, a series of dies, punches fitting the dies, a guide consisting of radially-movable wings slideable in grooves or channels in a casing, 130 springs by which said wings are normally retracted, and cams by which the wings may be advanced to fit and guide any size of punch. 135

5. In a device for forming seamless tooth-

5 crowns, a die-supporting stand, a series of dies, punches fitting the various-sized dies, a casing having a radially-slotted central portion, wings slidable in said slots and springs by which they are normally retracted, heads fitting the upper and lower ends of the casing having cam-shaped chambers into which the upper and lower ends of the wings project, and means for turning the wing-carrying center with relation to said cams, so that the wings are advanced or retracted.

6. In a device for forming seamless tooth-crowns, a die-supporting stand, a series of dies, a punch-guide consisting of an exterior 15 casing fitting the stand concentrically with the dies, the central portion turnable within the casing, a pin projecting through a slot in the casing by which it is turned, radial slots

formed in said center, and wings slidable therein, heads at each end of the casing having cam-shaped depressions into which the ends of the wings project whereby the turning of the center with relation thereto will advance or retract the wings and adjust them to guide any-sized punch.

7. The combination with a punch, of a guide therefor having radially-movable wings or parts whereby it may be adjusted to operatively receive punches of different diameters.

In witness whereof I have hereunto set my hand.

JOSEPH FRANKLIN TWIST.
